(57) **CLAIM**

I claim an ornamental design for a saw blade centering fixture, as shown and described.

DESCRIPTION

FIG. 1 is a top isometric view of a saw blade centering fixture showing my new design;

FIG. 2 is a top view of the saw blade centering fixture;

FIG. 3 is a front view of the saw blade centering fixture;

FIG. 4 is a right-side view of the saw blade centering fixture;

FIG. 5 is a left-side view of the saw blade centering fixture;

FIG. 6 is a back view of the saw blade centering fixture;

FIG. 7 is a bottom view of the saw blade centering fixture; and,

FIG. 8 is a bottom isometric view of the saw blade centering fixture.
